United States Patent Office.

EDMOND A. WARREN, OF BROOKLYN, NEW YORK.

Letters Patent No. 70,925, dated November 12, 1867.

IMPROVED PAPER-RULING MACHINE.

The Schedule referred to in these Letters Patent and making part of the same.

TO ALL WHOM IT MAY CONCERN:

Be it known that I, EDMOND A. WARREN, of Brooklyn, in the county of Kings, and State of New York, have invented a new and improved Paper-Ruling Machine, and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to a new and improved machine for ruling paper; and it consists of a rotating cylinder provided with nippers to grasp and hold the sheets of paper to be ruled, and also provided with adjustable cams, the above parts being used in connection with a pen-beam, and all constructed and arranged to operate as hereinafter fully shown and described.

The invention further consists in a novel and improved arrangement of conveying or carrying-cords, whereby the ruled paper is conveyed from the rotating cylinder, in which it is ruled, to the box or receptacle prepared to receive it, without the liability of being blurred or smudged, the device at the same time being very compact. In the accompanying sheet of drawings—

Figure 1, Sheet No. 1, is a side sectional view of my invention taken in the line $x\ x$, fig. 2.

Figure 2, a plan or top view of the same.

Figure 3, Sheet No. 2, a section of a portion of the same taken in the line $y\ y$, fig. 1.

Figure 4, a section of fig. 3 taken in the line $z\ z$, and looking in the direction of the arrows 1.

Figure 5, a section of fig. 3 taken in the line $x'\ x'$.

Figure 6, a section of fig. 3 taken in the line $z'\ z'$, and looking in the direction indicated by the arrows 2.

Similar letters of reference indicate like parts.

The main frame of the machine is composed of two uprights, A A, in which the shaft B of a cylinder, C, has its bearings. This cylinder is covered with a suitable cloth, and has two longitudinal openings, $\alpha\ \alpha$, made in it, extending its whole length, with a shaft, D, fitted in each opening, and having two fingers or jaws, E E, thereon. Each shaft D has a spiral spring, F, upon it, and these springs have a tendency to keep the fingers E in contact with or upon the periphery of the cylinder, which position is shown in fig. 1. Each shaft D has an arm, G, attached to its outer end, and these arms, as the cylinder C rotates, come in contact with a fixed cam, H, secured to the inner side of the opposite upright A of the frame, and cause the shafts D to be turned, and the fingers E to be raised at the proper time, so that they may receive the edges of the sheets, the fingers, under the influence of the springs F, closing at the proper time to clutch the edges of the sheets as the arms leave or pass the fixed cam H. I is an inclined feed-board, from which the sheets of paper are fed to the cylinder C. This feed-board has two parallel bars, b b, attached to it, which project beyond the lower edge of the feed-board, and a short distance above the inner part of the feed-board there is fitted, in suitable bearings, a shaft, J, having two arms or fingers, K K, attached to it, which are kept in contact with the ends of the bars b b by a spring, L, attached to a crank, e, at one end of shaft J, and to one of the uprights A. This shaft J has an arm, M, attached to it, the lower end of which projects within the line of rotation of two cams, N N, secured to one end of the cylinder C by set-screws d, which pass through curved slots e, in the plates of the cams, into the end of the cylinder, and admit of the adjustment of the cams, as will be fully understood by referring to fig. 6. The outer surfaces of the cams N N are "flush" with the peripheries of the heads or ends of the cylinder C, and said cams are made with their outer edges oblique, which gives them a taper form longitudinally, as shown clearly in fig. 2. These cams N N come in contact with the arm M, as the cylinder C rotates, and cause the shaft J to be turned sufficiently to raise the fingers K K, and admit, at the proper time, the sheet to pass to the open or raised fingers E of the shafts D D. Just in front of the shaft J the pen-beam O is placed, said beam being attached to a shaft, P, the bearings of which are in the upper part of the uprights A A. The pens Q, which may be of the usual construction, are kept in contact with the paper on the cylinder C by a spring, R, the lower end of which is secured to one of the uprights A, and the upper end attached to an arm, e, on one end of the shaft P. This shaft P also has an arm, S, attached to it, the lower end of which extends down within the path of the movement of cams T, attached to the end of the cylinder C opposite to the end where the cams

N N are attached. These cams are also made of taper form, and they may be adjusted further in or out from the centre of the cylinder, on account of their shanks being provided with oblong slots f, through which set-screws T pass into the end of the cylinder. These cams, as the cylinder C rotates, come in contact with the arm S, and raise the pens Q at the proper time, corresponding to the blank portions or spaces to be left on the sheets, and these spaces may be made of greater or less length by adjusting the arm S on the shaft P so that a greater or less surface of the cams T may act upon the arm. The same may be said of the arm M, which is also adjustable on the shaft J for the purpose of regulating the raising of the fingers K K. U (see more particularly fig. 1) represents a series of cords, which pass over a small roller, V, above the cylinder C, around a roller, W, near the front part of the base of the machine, and over and under rollers Y Y', at the discharge end of the base. (See fig. 1.) U' represents cords, which pass over a roller, Z, above roller W, and around a roller, Z', in front of roller W, and around the roller Y. The cords U U' convey the sheets from the cylinder C to the box or receptacle prepared to receive them, and, in order to prevent the smudging of the ruled sheets, the roller W may be covered by blotting-paper or other absorbent material. The cords U U' are driven by a belt, A', from the cylinder C.

Having thus described my invention, I claim as new, and desire to secure by Letters Patent—

1. The rotating cylinder C, provided with shafts D D, having fingers E, to grasp the sheets of paper to be ruled, in connection with the pen-beam O, provided with pens Q, and all arranged to operate in the manner substantially as and for the purpose set forth.
2. The adjustable cams N, at one end of the cylinder C, in connection with the arm M, on the shaft J, provided with fingers K K for presenting the sheets to the cylinder C, substantially as shown and described.
3. The adjustable cams T, at one end of the cylinder C, in connection with the arm S on shaft P, having the pen-beam O attached, substantially as and for the purpose specified.
4. The cords U U', arranged in relation with the cylinder C, and working, respectively, over the rollers Z Z' W Y Y' V, to operate substantially in the manner as and for the purpose set forth.

The above specification of my invention signed by me this 24th day of June, 1867.

EDMOND A. WARREN.
